(57) CLAIM

The ornamental design for a golf club sole plate, as shown and described.

DESCRIPTION

FIG. 1 is a perspective view of a golf club sole plate; FIG. 2 is a front elevational view thereof;

FIG. 3 is a rear elevational view thereof;

FIG. 4 is a toe end view thereof;

FIG. 5 is a plan view thereof; and,

FIG. 6 is a heel end view thereof.

The broken line showing is for illustrative purposes only and forms no part of the claimed design.
